UNITED STATES PATENT OFFICE.

GUSTAV F. HOCHRIEM, OF CHICAGO, ILLINOIS, ASSIGNOR TO RHODES-HOCHRIEM MANUFACTURING CO., OF CHICAGO, ILLINOIS, A CORPORATION OF ILLINOIS.

COIN-SLOT CLOSURE FOR SCALES.

Application filed June 26, 1926. Serial No. 118,672.

This invention relates to improvements in a coin slot closure for scales, and refers more particularly to an automatically operated shutter adapted to open and close the coin slot of a coin-controlled ticket-printing and delivering scale.

At the present time coin controlled ticket-printing and delivering scales are becoming popular with the public.

Briefly describing their operation: A person steps on the scale platform, and the depression of this platform sets in motion mechanism for bringing the printing member into printing position. In one type of scale now on the market this printing member takes the form of a rotating wheel having numbers on its periphery. It is obvious that the printing wheel will oscillate somewhat before coming to a balanced standstill. Some means must be provided, therefore, to prevent the insertion of a coin which prints the weight of the person standing on the scale platform on the ticket, after which the ticket is ejected, until the printing wheel has come to a stand-still and for this purpose there is provided an automatically operated shutter having a delayed movement communicated to it by the original movement started by a person stepping on the scale platform. This shutter normally closes the coin slot; but due to this delayed movement, it is automatically opened, thus permitting the insertion of a coin into the coin slot to actuate the ticket printing and delivering mechanism.

The present invention has for its object, therefore, to provide an efficient automatically operated coin slot shutter. In normal position, that is, when the scale is idle, this shutter normally closes the coin slot opening. When a person steps upon the scale platform, mechanism is set in operation which moves the shutter away from the coin slot opening, permitting the insertion of a coin. After the coin has been inserted and has actuated the ticket printing and ejecting mechanisms, such operation also functions to positively return the shutter to closed position.

The coin slot closure of the present invention has been so perfected that it is fool-proof, in that if a person steps off the scale platform without inserting a coin the shutter, which had been moved away from the

coin slot opening by the mechanism set in motion by the act of stepping upon the scale platform, will be automatically returned to normal position to close the coin slot opening. The device is characterized by its simplicity of parts, ease and certainty in operation, and many other features which will be more apparent from the following description.

The invention is further characterized, in that the shutter is only moved away from the coin slot when the person is standing on the scale platform and the mechanism is in proper position to function. At any other time the shutter is in position to close the coin slot opening. Under the control of the mechanism moving the shutter, I have also provided mechanism for automatically closing the shutter to a locked position when the supply of tickets is exhausted, thus preventing the insertion of a coin when the supply of tickets is exhausted.

In the drawings, Fig. 1, is a diagrammatic rear elevational view of scale mechanism operating the coin slot closure, this figure illustrating normal position. Fig. 2 is a similar view illustrating the position of the mechanisms after a person has stepped on the platform and before the insertion of a coin. Fig. 3 is a similar view showing the dotted and full lines the positions of the mechanism at the instant the coin functions to place certain mechanisms in operation and immediately subsequent thereto. Fig. 4 is a side elevational view partly in vertical section showing the mechanism for moving the shutter. Fig. 5 is a front view showing the shutter closing the coin slot. Fig. 6 is a similar view showing the shutter after having been moved away from the coin slot to permit the insertion of a coin. Fig. 7 is a diagrammatic front view showing the mechanism for locking the shutter in closed position when the supply of tickets has been exhausted.

In order to avoid confusion as to drawings, I have illustrated my invention as being applied to a type of ticket printing scale heretofore described in co-pending application filed jointly in my name and in the name of Seth A. Rhodes, Serial No. 200, filed January 2, 1925. In that application when a person steps upon the scale platform, said platform is depressed, which sets in motion

mechanism which raises the upright rod 1 having the pivotal connection at 2 with a rocker arm 3, pivoted at 4 on a central plate 5, on the front and back of which plate 5 most of the interior operating mechanism of the scale is supported. The rocker arm is pivotally connected at its other end, as shown at 6, to the downwardly extending rod 7, which is connected to any suitable means for absorbing the shock of the weight being placed upon the scale platform. As the rocker arm 3 is being rocked on the pivot 4, it will push upwardly an upright rod 8 which has detachable connection therewith, as shown at 9. Intermediate the length of this rod 8, it is provided with two sets of coil springs 10 and 11. The lower end of the spring 10 is supported by means of the collar 12, supported in fixed relation relative to the rod 8 by means of the set screw 13. A collar 14, having a vertical slot 15, is positioned on the rod above the spring 10 and confines the movement thereof, the slot 15 working in combination with a pin 16 mounted on the rod 8. In Fig. 1 the rod 8 is shown in normal position, while in Fig. 2 the rod 8 is shown as having been forced upward by the weight of a person stepping on the scale platform. As heretofore described, the upward movement of the rod 8 has forced the spring 10 and collar 14 upward until the upward face of the collar 14 has contacted an outwardly projecting lug 17 carried by a horizontal rod 18 pivotally mounted at 19 on the plate 5. The rod 18 has been caused to rock on its pivot 19 through the action of collar 14, forcing lug 17 upwardly. This upward movement of the rod 18 forces upwardly a rocker arm 20 disposed adjacent one edge of said arm 18 at substantially right angles thereto. This rocker arm 20 extends from the rear of the plate 5 through the slot 21 and projects a substantial distance in front of the front face of the plate 5. This rocker arm 20 is pivotally mounted intermediate its length as shown at 22 on the supporting bracket 23 which projects from the face of the plate 5. The front end of the rocker arm 20 is considerably reduced in thickness and projects, preferably, in the form of the rod 24. This rod 24 passes through an internal aperture 25 made adjacent one end of the cross-arm portion 26 of the shutter designated, as a whole, 27. This shutter 27 is mounted for pivotal movement intermediate the two ends of the arm 26 at the point 28 and supported on the spaced return bend portion 29 of a plate 30. The plate 30 is provided with internal slots 31 adjacent one edge, into which are adapted to be placed adjustable screws 32 connected to the bracket 33, which may be attached to the cabinet of the scale. Depending from the arm 26, which is mounted in substantially a horizontal plane, is a

downward projection 34, which is enlarged adjacent its lower edge, as shown at 35, which latter may be provided with an outwardly projecting extension 36. The purpose of the portion 35 and extension 36 is to prevent distortion or straining of the metal by the force a person might exercise to inject a coin 37 into the coin slot opening 38. The coin slot opening 38 communicates with a coin chute 39.

Now, summing up the operations which have taken place thus far: The person has stepped upon the platform, causing the rod 1 to rock the lever 3 and forcing the rod 8 upwardly. The upward movement of this rod has forced the rod 18 to rock upwardly on its pivot, which simultaneously forces the rear end of the rocker arm 20 to be forced upwardly, which rocking on pivot 22 forces the front end 24 downwardly. The front end 24 registering with the aperture 25 in the shutter 27 has positively forced one end downwardly, rocking on the pivot 28, which positively causes the depending projection 34, with portions 35 and 36, to move away from the coin slot opening 38. The machine is now ready to receive a coin.

To avoid any confusion, it may be here stated that the coil spring 11 and portions of the rod 8 which project above the lug 17 form no part of the present invention, being connected to a means for automatically regulating the inking ribbon feed.

Assume now that a coin has been inserted in the open coin slot 38, dropping through the coin chute 39 until it trips a coin trip lever (not shown), which in turn rocks the pivoted dog 40 away from the upright rod 41, permitting the said upright rod 41 to descend, due either to its own weight or to an auxiliary weight. The downward movement of the rod 41 carries with it one end of a cross-arm 42 having a roller 43. The cross-arm 42 has its other end pivotally mounted on the plate 5, as shown at 44. As the rod 41 descends, the roller 43 will ride over the surface of the latch 45 mounted for pivotal movement, as shown at 46, on a bracket 47, depending from the lower edge of the plate 5. The latch 45 is provided intermediate its length with a dog 48 which in normal position registers with one end of a lever 49, also pivoted at 4 of the plate 5. As the roller rides over the upper end of the latch 45, it will rock said latch outwardly, releasing the end of the lever 49 from engagement with dog 48. The opposite end of the lever 49 is greatly enlarged, as shown at 50, to provide sufficient weight to cause the said released end to move upwardly. Projecting from a side of the lever 49 is a lug 51 in which is mounted the set screw 52. The arrangement is such that as lever 49 rocks upwardly, the upper end of the said screw 52 will contact the lower

face of the lever 42, also forcing same upward simultaneously, until the rod 41 has again become latched in suspended position by means of the dog 40 heretofore described.

5 This is more clearly shown in full lines in Fig. 3.

As the weighted end 50 falls, it carries with it an upright rod 53 having a coil spring 54 positioned intermediate its length. 10 As shown more clearly in Fig. 4, this rod 53 projects through an aperture 55 in the end of the rocker arm 20 heretofore described.

Referring now more particularly to Fig. 3, 15 the upper end of the rod 53 is provided with a screw-threaded collar 56 functioning to compress the spring 54 between it and the upper face of the rear end of rocker arm 20. This movement serves to force said 20 rear end of the rocker arm 20, as well as the free end of arm 18, downwardly, as shown in Fig. 3, which restores the coin slot shutter 27 to normal position (Fig. 5), closing the coin slot opening 38. Excess movement of the shutter 27 is prevented by means 25 of the projecting lug 57, Fig. 5.

Summing up, now, the operations which by the insertion of a coin have moved the shutter 27 to a position closing coin slot 38,— 30 a coin caused rod 41 to descend, carrying with it the roller 43. The roller 43, riding on the latch 45, released an end of lever 49 from engagement with dog 48, causing said released end to move upwardly, due 35 to the weighted end 50 which descends. In its upward movement the said released end of lever 49 caused the lever 42 to be restored to suspended position by means of the set screw 51. The downward movement of the 40 weighted end 50 of lever 49 forced downwardly the rod 53, causing a contraction of the spring 54 between the upper surface of the rear end of rocker arm 20 and the collar 56, which in turn forced said rear end 45 of rocker arm 20 downwardly, as well as the free end of arm 18. This caused the rocker arm 20 to rock on pivot 22, the pin end 24 being forced upwardly to normal position as shown in full lines in Figs. 4 and 5. The position of the mechanism as shown 50 in Fig. 3 corresponds to the position assumed after the insertion of a coin, the printing and ejection of a ticket, and while the person is still standing on the scale platform. It will thus be immediately obvious 55 that the present invention provides an automatically operated shutter for the coin slot opening by which the weight of a person stepping on the platform sets into force 60 mechanism which moves said shutter away from its normal position and permits insertion of a coin. The insertion of the coin tripped mechanism which simultaneously printed and ejected the ticket and restored 65 the shutter to a position closing the coin

slot opening. This movement of the shutter to closed position has been accomplished while the person is still standing on the scale platform.

It will be immediately obvious that the 70 device is absolutely foolproof and performs with an absolute certainty of operation.

Returning for a moment to the lever 3, when it has been forced upwardly by the weight of a person stepping on the platform through the raising of rod 1, a lug 75 58 projecting from one side forces upwardly a latch 59 pivoted at 60 and held under spring tension by the coil spring 61. After the lug 58 has been moved above the shoulder or dog 62 on the upper end of said latch, said latch will, through the coil spring 61, rock to normal position. The arrangement is such that when a person steps upon the scale the coin slot shutter 27 is opened. 80 To prevent the shutter 27 from remaining in an open position if such person steps off the scale without inserting a coin, I have allowed enough play between the lug 58 and dog 62, as clearly shown in Fig. 2, to 85 move said shutter to closed position by the lug 58 moving into contact with dog 62. It may be well to explain this action more in detail. As the person steps off the platform without inserting a coin, the levers in the 90 scale base which cause the upright rod 1 to be raised when the person stepped on the scale platform, are restored to normal position, and in this restoration, the rod 1 will be pulled downwardly carrying with it the 95 lever 3 from the side of the projected lug 58. If the latch 59 were not in the path of movement of the lug 58, the rod 1 pulling on the lever 3, through the mechanism in the scale base returning to normal position, would restore the lever 3 and rod 1 to 100 normal position, such as illustrated in Fig. 1. This is not possible, since the lug 58 will engage in the shoulder or dog 62 of the latch 59, thus latching the lever 3 in 105 suspended position. There will be some movement in a downward direction of rod 1, tending to restore the arm 3 to normal position since, as illustrated in Fig. 2, the arrangement is such that there is some space 110 between the face of the lug 58 and the upper face of the shoulder 62. This slight rocking of the arm 63 will be transmitted through the rod 8 and levers 18 and 25 to rock the coin slot shutter 27 back to 115 closed position.

Returning now to the position of the mechanism shown in Fig. 3. When a person steps off the scale platform, the latch 59 having been moved outwardly by the lug 51 on the lever 49, the movement of the platform will cause the rod 1 to descend, which sets in motion elements to restore the mechanisms described to the normal positions shown in Fig. 1. 120

This latter operation is fully described in said co-pending application, and needs no description here, as it forms no part of the present invention.

5 It will be apparent from the foregoing that the shutter of the present invention will be in closed position at all times except when a person is standing upon the scale platform and the mechanism is in 10 proper condition to function.

As a further feature of the present invention, depending from the rocker arm 20, intermediate its length, is a rod 63. This 15 rod 63 is connected to one end of a cross-bar 64 pivoted at 65. The other end 66 of this crossbar extends into the plane in which the vertical movable ticket support 67 travels. For the purpose of more clearly bringing out the function of arm 64 and 20 rod 63, I have shown in Fig. 7 a diagrammatic front elevational view of a ticket printing scale such as is shown in said co-pending application. 67 designates a support on which are anchored springs 68. A 25 rod 69 extends upwardly from the plate 67 to a ticket support 70, on which tickets 71 are mounted and moved upwardly between the vertical walls of a magazine 72. Tickets are fed to the printing mechanism singly by 30 means of the ejector 73, forcing tickets to a printing wheel 74. A printing ribbon 75 imprints the desired impression on the ticket. A hammer, not shown but actuated by 35 the insertion of the coin, produces the desired impression.

In operation, as each ticket is singly ejected from the stack 71, the springs 68 will maintain a constant pressure on said stack, forcing same upwardly so that a ticket 40 is always available at the top of the stack. As the stack decreases, the plate 67 will move upwardly. When there is only a small number of tickets left in the magazine, the plate 67 in its upward movement will contact the 45 end 66 of the arm 64, rocking said end upwardly on pivot 65 and forcing the opposite end downwardly. This opposite end is the end which is connected to the rod 63, which of course will also be forced downwardly. The downward movement of rod 50 63 will force the rear end of the rocker arm 20 downwardly and, rocking on the pivot 22, will force the pin end 24 upwardly to move the shutter 27 to the closed position shown 55 in Fig. 5. Any subsequent movement of the scale platforms by persons stepping thereon after the supply of tickets has been exhausted will not move the shutter 27. This particular feature will overcome many 60 complaints lodged against weighing scales.

I claim as my invention:

1. A coin slot closure mechanism for coin-controlled ticket printing scales comprising in combination a lever actuatable by a weight 65 being placed on the scale platform, an up-

right rod connected to said lever, a pivotally mounted arm having cooperative engagement with said upright rod, a second arm extending at substantially right angles to said first mentioned arm and cooperatively associated therewith, a movably mounted coin slot shutter engaged by said second arm and functioned by the movement of the latter to open or close the coin slot opening. 75

2. A coin slot closure mechanism for coin-controlled ticket printing scales comprising in combination a lever actuatable by a weight being placed on the scale platform, an upright rod connected to said lever, a pivotally mounted arm having cooperative engagement with said upright rod, a second arm extending at substantially right angles to said first mentioned arm and cooperatively associated therewith, a movably mounted coin slot shutter engaged by said second arm and functioned by the movement of the latter to open or close the coin slot opening, a lever actuatable by mechanism 80 set in motion by the insertion of a coin, means connected thereto and having cooperative engagement with said second arm whereby normal movement of said second lever after insertion of a coin returns the shutter to closed position. 85

3. A coin slot closure mechanism for coin-controlled ticket printing scales comprising in combination a lever actuatable by a weight being placed on the scale platform, an upright rod connected to said lever, a pivotally mounted arm having cooperative engagement with said upright rod, a second arm extending at substantially right angles to said first mentioned arm and cooperatively associated therewith, a movably mounted coin slot shutter engaged by said second arm and functioned by the movement of the latter to open or close the coin slot opening, a lever actuatable by mechanism 90 set in motion by the insertion of a coin, means connected thereto and having cooperative engagement with said second arm whereby normal movement of said second lever after insertion of a coin returns the shutter to closed position. 95

3. A coin slot closure mechanism for coin-controlled ticket printing scales comprising in combination a lever actuatable by a weight being placed on the scale platform, an upright rod connected to said lever, a pivotally mounted arm having cooperative engagement with said upright rod, a second arm extending at substantially right angles to said first mentioned arm and cooperatively associated therewith, a movably mounted coin slot shutter engaged by said second arm and functioned by the movement of the latter to open or close the coin slot opening, a lever actuatable by mechanism 100 set in motion by the insertion of a coin, means connected thereto and having cooperative engagement with said second arm whereby normal movement of said second lever after insertion of a coin returns the shutter to closed position. 105

4. A coin slot closure mechanism for coin-controlled ticket printing scales comprising in combination a lever actuatable by a weight being placed on the scale platform, an upright rod connected to said lever, a pivotally mounted arm having cooperative engagement with said upright rod, a second arm extending at substantially right angles to said first mentioned arm and cooperatively associated therewith, a movably mounted coin slot shutter engaged by said second arm and functioned by the movement of the latter to open or close the coin slot opening, and means, including a movable latch and lever functioning to return said shutter to normal position, closing the 115

110

115

120

125

130

coin slot opening, when a weight is removed from the scale platform, without the insertion of a coin.

5. A coin slot closure mechanism for coin-controlled ticket printing scales having a ticket magazine, comprising in combination a lever actuatable by a weight being placed on the scale platform, an upright rod connected to said lever, a pivotally mounted arm having cooperative engagement with said upright rod, a second arm extending at substantially right angles to said first mentioned arm and cooperatively associated

therewith, a movably mounted coin slot shutter engaged by said second arm and functioned by the movement of the latter to open or close the coin slot opening, and means for automatically moving said shutter to close the coin slot opening when the supply of tickets in the magazine is substantially exhausted, including means connected to said shutter and having cooperative engagement with a ticket support movable up and down in said magazine. 15 20

GUSTAV F. HOCHRIEM.
